United States Patent Office

Des. 186,755
Patented Nov. 24, 1959

186,755

HAND BAG

John I. Horner, Venice, Calif.

Application July 20, 1959, Serial No. 56,861

Term of patent 14 years

(Cl. D87—3)

Fig. 1 is a front elevational view of a hand bag, showing my new design;

Fig. 2 is a side elevational view of the hand bag;

Fig. 3 is a top plan view of the hand bag;

Fig. 4 is a bottom plan view of the hand bag; and

Fig. 5 is a perspective view of the hand bag, showing the top and bottom sections thereof separated.

I claim:

The ornamental design for a hand bag, as shown.
